UNITED STATES PATENT OFFICE

2,385,936

DARNING MACHINE

John Page and Leslie Trevor John Page,
Leicester, EnglandApplication June 24, 1944, Serial No. 541,960
In Great Britain October 27, 1943

3 Claims. (Cl. 66—2)

This invention is a darning machine, for darning socks and the like. The said machine comprises a curved needle bed for the reception of individually-slidable bearded needles presenting their beards at the convex surface thereof, which bed affords a passage for butts of the needles to be presented at the concave surface of the bed, oscillatable cam means located in the concavity of the bed for engaging said butts and for imparting knitting movements to the needles during oscillation of the cam means in each direction, a yarn feeder, presser means arranged about the curved bed for pressing the bearded needles, a mounting on which said presser means is displaceable away from the bed to permit a sock or the like to be inserted or removed, and means for oscillating said cam means and feeder in relation to the needle bed. This machine preferably has, in combination with a fabric take-up device, a holding-down device for engaging the exterior of the fabric, and means for periodically lifting the holding-down device coincidently with a step-by-step operation of the take-up. A further feature of the invention resides in the provision of a curved sinker bed for the reception of individually-movable sinkers, and sinker operating means partaking of the oscillation between the needle bed and feeder.

These and other features of the present invention are incorporated in the darning machine which will now be described in detail as an example, with reference to the accompanying drawings in which

Figure 1 is to some extent diagrammatic in character and shows a sectional elevation of the machine, and

Figure 2 is a view, partly in section, looking on the left hand end of Fig. 1.

Upon a suitable base 10 there is a bracket 11 within which a hollow rock shaft 12 is journaled. This rock shaft is provided with any suitable means for oscillating it; the handle 13 is shown by way of example and any power drive may be used. An external cylinder 14 is secured to the bracket 11 and contains a needle cylinder. The said needle cylinder is formed in two portions, the front portion 15a and a rear portion 15b. The upper part of the front cylinder 15a has its outer periphery tricked to accommodate a suitable number of bearded knitting needles 16. The tricks are cut completely through the front part of the rear portion 15b as indicated at 17, the interior diameter of the said front part being enlarged for this purpose (which enlargement is clearly shown in the bot-

tom portion of the drawing). Therefore the butts 18 of the needles can project inwardly through the cylinder portion 15b for engagement by operating cams, and it may here be pointed out that while the needle hooks are presented at the outer or convex surface of the needle bed the butts are presented at the inner or concave surface thereof.

Inside the needle cylinder there is a cam drum 20 secured to the rock shaft 12. This cam drum is formed with a suitable knitting track, indicated diagrammatically at 21, in which the butts of the needles are received, the shape of said cam track being such that as the cam drum is oscillated knitting proceeds to and fro along the line of the needles, the necessary knitting thread being laid to and fro along the line by a yarn feeder 22 supported from an arm 23 attached to the rock shaft.

10 Around the aforesaid end of the needle cylinder at which the needle heads are presented there is a part-circular member 50 which carries a series of pressers 51 projecting radially inwards at position such that as the bearded needles 16 are operated by the cam drum 20 each one engages its presser and is pressed thereby so that upon retraction of each needle the latter casts off its old loop in known manner. This part-circular member 50 is carried by an arm 52 which 15 extends horizontally above the needle cylinder and is pivoted at 53 so that the arm and said member may be swung upwards as is necessary in order to permit a sock or the like, which requires darning, to be drawn on to the exterior of the stationary cylinder 14.

The said part-circular member 50 further constitutes a sinker bed, being tricked radially to accommodate individual loop-measuring sinkers 54. These sinkers 54 have butts 54' which are 20 presented at the rear of the part-circular member to engage a sinker-operating cam 55 which oscillates with the feeder 22, the said cam 55 being so shaped and positioned that each sinker is advanced inwards between a pair of needles and is then retracted in the appropriate time relationship with the passage of the feeder. The said part-circular member 50 further incorporates a holding-down device which engages the exterior of the fabric just beyond the aforesaid end of the cylinder and urges it inwards over the verge of the cylinder. This device consists of a curved strip of metal 56 attached at its ends to the said member 50 but having its outer periphery at such a radius that the heads of the needles 16, when projected, pass outside it. In order

that this holding-down device 56 shall not inhibit the action of the take-up device herein mentioned, the part-circular member 50 carrying it is raised slightly at the end of each swing of the cam drum 20 at the time when the take-up device is racked outwards. For this purpose, at each side of the cylinder there is a tappet 57 on which tappets the ends of the part-circular-member 50 rest, and these tappets are raised at the end of each swing by mechanism which is driven by the aforesaid handle 13.

The tappets 57 rest on vertical plungers 58 slideable in housings 59 within the box-like base 10 and connected by a horizontal cross bar 60 resting on cam 61. The shaft 62 of this cam is driven at twice the speed of the cam drum 20 by gearing, preferably chain-and-sprocket gearing, indicated at 63.

The take-up device consists of a disc 26 the periphery of which is provided with a series of sharp pins 64 which engage the interior of the sock. The shaft 27 on which this disc 26 is mounted extends into the interior of the cam drum 20, but in order to provide an outer bearing for the shaft the aforesaid end of the cylinder is closed by plate or the like 65 through which the shaft extends axially. The shaft 27 is prevented from rotating by a spring-pressed key or dowel 66 in the plate 65 engaging in a key-way 67 along the shaft. The take-up device may be returned by first rotating it and by then pushing it inwards, for which purpose the key-way 67 consists of two parallel branches connected at the ends. The take-up shaft 27 is provided with a rack of ratchet teeth 28. These teeth are engaged by a pawl 29 pivoted at 30 between a pair of arms 31 themselves pivoted at 32 in a bracket 33 secured to the interior of the cylinder 15a. The said arms carry a plate 34 which is urged by a spring 35 towards the end of the cam drum 20. The latter is provided with two spaced cams 36 so located that in each direction of movement of the drum one of them engages the plate 34 and pushes the pawl to the left and so moves the ratchet shaft 27 outwards. Thus the take-up mechanism makes a step at the end of each course of knitting. The pawl is urged into engagement with the rack by a spring 37.

The feeder 22 is carried by a post 68 depending from a plate 69 attached to an arm 24 pivoted to arm 23. At its rear end the post 68 carries a projecting pin 71 that travels inside a part-circular rim 72 on member 50 so that the feeder is prevented from rising. The pin 71 may be disengaged from the rim 72, and the sinker cam 55 from the sinker butts 54', at the end of either swing, so that the feeder and the pressers may then be swung away from the needles.

At each end of the group of needles 16 in the cylinder there is a dummy needle 16a, without a hook, the function of which is to penetrate the fabric at the side of the hole to be darned and so to position the fabric while at least one needle inwards thereof operates.

Any suitable means may be provided for varying the number of needles operated on by the knitting track in the cam drum. For this purpose the needles may have double butts.

It is to be understood that at the commencement of darning operations the sock is positioned around the exterior of the cylinder 14 and underneath the holding-down device 50 so that the needles penetrate it in their outward movement,

receive the yarn from the feeder 22 and form stitches during their retraction.

We claim:

1. A darning machine comprising a curved needle bed for the reception of individually-slidable bearded knitting needles presenting their beards at the outer convex surface of the bed at an end thereof which bed affords a passage for butts of the needles to be presented at the concave surface of the bed, oscillating cam means located in the concavity of the bed for engaging said butts and for imparting knitting movements to the needles during oscillation of the cam means in each direction, a yarn feeder, presser means arranged about the said end of the curved bed for pressing the bearded needles, a mounting on which said presser means is displaceable away from the bed to permit a sock or the like to be inserted or removed, means for oscillating said cam means and feeder in relation to the needle bed, a fabric take-up device, means for operating it with a step-by-step motion to take up the fabric as darning proceeds, a holding down device for engaging the exterior of the fabric, and means for periodically lifting the holding-down device coincidently with the step-by-step operation of the take-up.

2. A darning machine comprising a curved needle bed for the reception of individually-slidable bearded knitting needles presenting their beards at the outer convex surface of the bed at an end thereof which bed affords a passage for butts of the needles to be presented at the concave surface of the bed, oscillating cam means located in the concavity of the bed for engaging said butts and for imparting knitting movements to the needles during oscillation of the cam means in each direction, a yarn feeder, presser means arranged about the said end of the curved bed for pressing the bearded needles, a mounting on which said presser means is displaceable away from the bed to permit a sock or the like to be inserted or removed, means for oscillating said cam means and feeder in relation to the needle bed, a curved holding-down device for engaging the exterior of the fabric, means for raising it periodically, a fabric take-up device, and racking mechanism for imparting a take-up step to said device each time the holding-down device is raised.

3. A darning machine comprising a curved needle bed for the reception of individually-slidable bearded knitting needles presenting their beards at the outer convex surface of the bed at an end thereof which bed affords a passage for butts of the needles to be presented at the concave surface of the bed, oscillating cam means located in the concavity of the bed for engaging said butts and for imparting knitting movements to the needles during oscillation of the cam means in each direction, a yarn feeder, presser means arranged about the said end of the curved bed for pressing the bearded needles, a mounting on which said presser means is displaceable away from the bed to permit a sock or the like to be inserted or removed, means for oscillating said cam means and feeder in relation to the needle bed, a sinker bed for the reception of individually-movable sinkers, a mounting on which said bed is displaceable away from the needle bed to permit a sock or the like to be inserted or removed, and oscillatable sinker-operating means.
